SPECIFICATION forming part of Design No. 14,636, dated February 5, 1884.

Application filed December 21, 1883. Term of patent 3½ years.

To all whom it may concern:

Be it known that I, FRANK E. SMITH, a resident of New York city, in the county and State of New York, have invented and produced a new and original Design for a Carpet, of which the following is a full description, in connection with the accompanying photograph, which represents a face view of my new design for a carpet.

10 This invention relates to a new ornamentation of the face of a carpet, oil-cloth, or analogous fabric.

In the accompanying photograph are shown three principal bands, A, B, and C, into which

the face of the carpet is divided. The band 15 A is ornamented by the scalloped figures *a*. The band C contains different figures, indicated in the photograph, of which the more important are the bunches of flowers and leaves *b*, *d*, and *e*. 20

I claim—

The design for a carpet, the same consisting of the figures A, B, C, *a*, *b*, *d*, and *e*, substantially as shown.
